UNITED STATES PATENT OFFICE

EUGENE SCHWARTZ, OF PHILADELPHIA, PENNSYLVANIA, ASSIGNOR TO KETTERLINUS LITHOGRAPHIC MFG. CO., OF PHILADELPHIA, PENNSYLVANIA, A CORPORATION OF PENNSYLVANIA

CARDBOARD DISPLAY DEVICE

Application filed September 11, 1929. Serial No. 391,750.

This invention relates to signs and more particularly to a sign adapted to be used, primarily, for advertising purposes, and to be very economically constructed from a 5 single sheet of heavy paper or cardboard. The sign of the invention is intended to stand perpendicularly with respect to the wall, post, or other support to which it is secured.

One object of the present invention is to provide a sign of the character under consideration in which a single blank is employed for forming an upright of single thickness to depict for example bottles, cans, boxes, or any other article that it is desired 15 to advertise.

A further object of the present invention is to provide a sign of the character stated in which a single sheet of material is employed stamped out to form a one-piece wall or like support, and a one-piece advertising member is extended therefrom at right angles thereto and detachably secured with respect to the wall support by means of interlocking 25 flaps.

Other and further objects of the present invention reside in the provision of general details of construction and in the arrangement and combination of parts for attaining 30 the results sought by the foregoing objects.

The invention consists of the novel construction hereinafter described and finally claimed.

For the purpose of illustrating my invention I have shown in the accompanying drawings one form thereof which is at present preferred by me, since the same has been found in practice to give satisfactory and reliable results, although it is to be understood that the various instrumentalities of 35 which my invention consists can be variously arranged and organized and that my invention is not limited to the precise arrangement and organization of the instrumentalities as herein shown and described.

The nature, characteristic features and scope of the invention will be more fully understood from the following description taken in connection with the accompanying 50 drawings forming part hereof, and in which:

Fig. 1 is a view in perspective of a sign embodying the invention.

Fig. 2 is a view in end elevation of the parts shown in Fig. 1.

Fig. 3 is a fragmentary view illustrating 55 certain parts as shown in Fig. 1.

Fig. 4 is an edge view of Fig. 2; and

Fig. 5 is a fragmentary view in elevation illustrating the sign shown in Fig. 1 before 60 it is folded over upon itself to effect an interlock of parts.

Referring to the drawings in detail, the sign of the invention is formed from a single blank and comprises a wall bracket 10 arranged to be secured as at 11 to a support, and an advertising portion extended therefrom arranged at right angles thereto, best seen at 12 in Fig. 1. The part 12 may be made to represent bottles, cans, boxes, or any other article that it is desired to advertise. The single web or advertising portion of the device is held in position at right angles with respect to the wall bracket 10 by means of the upper and lower parts 13 and 14. These parts are each notched as at 15 to engage the notched parts 16 of the advertising web 12 and are arranged at an inclination with respect to the part 12, as clearly shown in Fig. 1. The notched parts extend upon opposite sides of the member 12.

In erecting the sign, the bracket member 10 is brought to the relation shown and then tacks, or other securing elements, are driven into a wall or like support 17. This arrangement provides a structure of considerable strength and one which will hold the main body of the sign, constituted by the web, substantially perpendicular with respect to the wall or other support to which it is secured. It is much cheaper than the metal, but in use answers the same purpose of a metal sign. It may have advertising placed upon both sides of the sign. I am aware that the invention may be embodied in other specific forms without departing from the spirit or essential attributes thereof, and I therefore desire the present embodiment to be considered in all respects as illustrative and not restricted, reference being had to the appended claims 100

rather than to the foregoing description to indicate the scope of the invention.

Having thus described my invention, what I claim as new, and desire to secure by Letters Patent, is:

1. A device of the character stated formed from a single blank of card board and folded to provide a single elongated vertically disposed wall attachment part having a single vertically disposed advertising portion extended therefrom at right angles thereto, and upper and lower angular flaps extended from said wall attachment part at an inclination thereto, which flaps assume a substantially V-relation-ship with respect to said wall attachment part for engaging said advertising portion at its top and bottom edges to maintain same at right angles with respect to said wall attachment part.
2. A device of the character stated formed from a single blank of cardboard and folded to provide a single elongated vertically disposed wall attachment part having a single vertically disposed advertising portion extended therefrom at right angles thereto, and upper and lower oppositely disposed angular flaps extended from said wall attachment part at an inclination thereto for engaging said advertising portion to maintain the same at right angles with respect to said wall attachment part, said angular inclined flaps and said advertising portions each having their edges notched for co-operative engagement, said flaps in their interlocked position assuming in cross-section substantially V-relation-ship with respect to said wall attachment part.
